UNITED STATES PATENT OFFICE.

OSCAR J. ECKLAND, OF OWOSSO, MICHIGAN.

INTERNAL-COMBUSTION ENGINE.

Application filed May 19, 1926. Serial No. 110,228.

This invention relates to internal combustion engines, particularly that type embodying a plurality of pistons with means for compressing a charge prior to its admission into the explosion chamber, and has for its object the provision of a novel engine embodying a plurality of simultaneously acting pistons together with charge forming devices including a plurality of valves whereby an explosive mixture will be admitted to the engine, compressed and then conducted into the explosion chamber, this cycle of operations occurring at every explosion stroke, it being consequently apparent that a greater degree of power may be developed than is ordinarily possible.

An important object is to provide an engine of this character so constructed and arranged that lateral strain will be prevented at all times so that the pistons may glide freely within the cylinders without likelihood of wearing the cylinders "out of round".

Still another object of the invention is to provide an engine in which the crank case is entirely separated from the cylinders, leakage at this point being consequently entirely avoided.

Still another object is to provide an engine in which the various piston elements are all carried by the same piston rod, it being consequently impossible for there to be any relative movement between the various pistons.

A further object of the invention is to provide an engine of this character provided with a novel arrangement of intake and exhaust ports together with by-pass elements permitting the previously compressed charge of gas or explosive mixture to pass from the compressing chamber to the explosion chamber in an automatic and absolutely efficient manner.

An additional object is to provide an engine of this type which will be comparatively simple and inexpensive in manufacture, easy to set up and use, positive in action, efficient and durable in service, and a general improvement in the art.

With the above and other objects and advantages in view, the invention consists in the details of construction, and the arrangement and combination of parts to be herein-

after more fully described and claimed, and illustrated in the accompanying drawings, 55 in which:—

Figure 1 is a vertical cross section through an engine constructed in accordance with this invention, and

Figure 2 is an end elevation, partly broken 60 away and in section, illustrating the valve arrangement and operating means.

Referring more particularly to the drawings, the numeral 10 designates the base of the engine upon which is formed or with 65 which is connected the crank case 11 which may be of any preferred or ordinary construction and formed of any suitable or necessary number of parts detachably or otherwise connected, the former being preferable in order to give access to the interior 70 for the purpose of making repairs, adjustment and replacement. In the present instance this crank case is represented as provided at opposite sides with removable cover 75 plates 12 and 13, the latter being provided as a closure for an extension housing 14. Journaled through the crank case is the crank shaft 15 and journaled through the housing 14 is a cam shaft 16 driven from the 80 crank shaft as by means of intermeshing gears 17 and 18 respectively. Externally of the crank case, the crank shaft 15 preferably carries a fly wheel 19 and there is counterbalancing means or weight means indicated at 20 to compensate for the connecting rod 21 which is connected with the crank portion 22 of the crank shaft. Throughout 85 this portion and the remaining portion of the description, it will be observed that reference 90 is made to only a single cylinder, but this is merely for convenience in description inasmuch as it is quite obvious that the engine constituting or embodying the invention may be provided with any desired number of 95 cylinders, as will be readily apparent.

Suitably secured to or formed upon the upper portion of the crank case is a cylinder block 23 beneath which is secured a cross head guide 24 which extends downwardly 100 into the crank case as clearly illustrated in Figure 1. The bottom of the cylinder block 23, which bottom is indicated by the reference character 25, is provided with a stuffing box or packing gland 26 through which is 105 slidably mounted a piston rod 27 equipped at

its lower end with a cross head 28 slidably mounted along the guide 24, this cross head carrying a wrist pin 29 with which the connecting rod 21 above described is connected.

5 The cylinder block 23 is of the usual or well known double walled construction to provide a water jacket 30 provided for cooling purposes, any ordinary or preferred inlet and outlet connections, not shown, being provided therefor. The top of the cylinder 31 within the cylinder block is closed by a head 32 of hollow formation having connected therewith a pipe or conduit 33 which communicates with a chamber 34 formed within 10 an extension or housing member 35 on one side of the cylinder block.

15 The cylinder block is provided with two separate ports 36 and 37 which lead into the chamber 34, these ports being separated by a partition 38. It should be stated that communication between the chamber 34 and the ports is controlled by means of valve mechanism to be described. The chamber 34 is adapted to be connected with a conduit 39 which leads from any suitable carburetor, not shown, so that an explosive mixture may be supplied to the chamber and eventually to the engine in a manner to be described. The top wall 40 of the chamber 34 is provided with two valve openings and seats 41 and 42 with which cooperate valves 43 and 44 carried by depending valve stems 45 and 46 urged into closed position by spring devices 47 and having suitably connected therewith push rods 48 and 49 terminating in heads 50 engaged by suitable cams 51 on the cam shaft 16. The arrangement of the cams is of course such that when one push rod is elevated the other is in lowered position, 20 and vice versa. The top walls 52 of the passages 53 which are adapted to establish communication between the ports 36 and 37 and the chamber 34 are preferably provided with threaded openings 54 normally closed 25 by removable screw plugs 55 provided for the purpose of permitting access to the valves 43 and 44 for effecting grinding or replacement thereof, as may be required after the engine has been in service for a 30 prolonged period. Obviously, in view of the opposed relation of the cams 51 cooperating with the push rods 48 and 49, the valves 43 and 44 will be opened and closed in alternation for a purpose to be hereinafter explained.

35 At a point intermediate its length, the cylinder is provided with an exhaust port 56 with which may be connected any suitable exhaust pipe 57 or which may be permitted to discharge directly into the atmosphere, this detail being immaterial. It might be mentioned in passing that the valve 43 may be considered the intake valve, the valve 44 the discharge valve, and the port 56 of course 40 the exhaust.

45 The bottom wall 58 of the cylinder head is provided with a valve opening and seat 59 with which cooperates a valve 60 carried by a stem 61 projecting upwardly, through and beyond the top wall of the cylinder head 50 and normally urged into closed position by a spring 62. The upper end of the valve 60 is engaged by one end of a rocker arm 63 which is suitably pivotally or rockably mounted upon the top of the cylinder head and which has connected therewith a downwardly extending push rod 64 slideable through suitable bores or openings in the partition member 38 and having its lower end engaged by a cam on the cam shaft 16 55 in the same manner as the head 50 on the lower ends of the push rods 48 and 49 are engaged by the cams 51. Obviously, at certain in the rotation of the cam shaft 16, the rocker arm 63 will be operated to open the valve 60, closing thereof being subsequently effected by means of the springs 62.

60 Ignition of the explosive charge which enters the engine from time to time or at the different cycles thereof may be effected by means of any suitable ignition circuit, system or apparatus embodying or connected with an ordinary or any preferred type of spark plug 65 mounted in the cylinder head, or at any other place, as may be preferred.

65 Mounted on the piston rod 27 within the cylinder 31 is a compression piston 66 and a power piston 67, both suitably packed with piston rings or the like and mounted of course in the proper relation with respect to each other upon the piston rod 27.

70 In explaining the operation of the engine up to this point, let it be assumed that a start is made with the crank 22 at the bottom of the stroke, both pistons 66 and 67 and the cross head 28 being at their lowermost positions. Assuming that the start is made on the upstroke of the piston, the valve 43 opens, the opening controlled thereby being open to the carburetor. The lower piston 66 then sucks in a charge of explosive mixture while the power piston 67 is entirely without charge. The lower piston 66 reaches a point to within say one-eighth of an inch of the upper limit of its stroke and at this point the valve 43 closes. Coming down on the other half of the stroke, the lower piston 66 compresses the charge previously drawn in by the opening of the valve 43 and this compression occurs until both pistons arrive to a point within approximately one-half an inch of the bottom of their stroke. At this point, the valve 44 opens, then three degrees later, with respect to the movement of the crank shaft, the valve 60 opens. The charge previously compressed below the piston 66 then passes out through the port 37 and valve seat 42 through the conduit or pipe 33 and then passes through the valve opening 59 into the cylinder above the upper piston 75 80 85 90 95 100 105 110 115 120 125 130

67. As the pistons again rise on the second revolution, the valve 43 opens, permitting a fresh charge to enter while the upper piston 67 is compressing the charge between it and 5 the top of the cylinder. When the pistons reach a point within twenty degrees of the cylinder head, with respect to the rotation of the crank shaft, the compressed charge is ignited and the pistons 67 and 66 start down- 10 wardly on their second stroke. As these pistons reach a point within approximately a half inch of the bottom, the valve 44 opens and the top piston 67 is just starting to uncover the exhaust port 56. When the pistons 15 reach the lower end of their stroke, the exhaust port 56 is entirely opened so that the burnt gases from the ignited charge may escape into the atmosphere. This is the complete cycle of operation in so far as the explosive feature is concerned.

An important feature in the construction and arrangement of this engine is the provision of a novel oiling system which may include a force feed, oil cup or a combination 20 of both, or in fact any other equivalent arrangement whereby oil may enter the cylinder at opposite sides as, for instance, through the pipes indicated at 68 and 77, the cylinder wall being correspondingly ported 25 at diametrically opposite points to permit this. Attention is directed to the fact that these oil holes are located at the center with respect to the two pistons and it will therefore be apparent that there will never be 30 any back pressure on the oil cups or other feed means inasmuch as there is always a charge beneath the lower piston 66. It will also be observed that there is a cushioning or rather taking off of the jar from the reciprocating parts, a feature which cannot 35 ordinarily be accomplished in the regular type of oil or gas motor. It will also be seen that there is a possibility of obtaining a perfect mixture in the motor especially for the reason that the charge is initially sucked into 40 the motor, compressed and then transferred to the explosion chamber, the entire movement occurring at high velocity which will certainly insure perfect combustibility. Another feature of advantage is that the valves 43 and 44 are always cooled by the water 45 jacket structure and that the valve 60 will not warp owing to the fact that there is always a charge going past it. The elimination 50 of the usual type of poppet exhaust valve will be of great benefit inasmuch as there is danger of warping, in case one is provided, owing to the intense heat generated at this particular point.

60. From the foregoing description and a study of the drawings, it will be apparent that I have thus provided a simply constructed, easily assembled and controlled internal combustion motor which will possess 65 all the advantages ascribed to it in the intro-

ductory remarks and which should have a long life and give unusually satisfactory service.

Another very important feature of advantage is that owing to the provision of the cross head 28 which cooperates with the guides 24, there will never at any time be any lateral strain upon the pistons 66 and 67, it being quite obvious that therefore the pistons may glide upwardly and downwardly 70 in a true reciprocatory fashion without there being any likelihood of lateral strain coming upon the cylinder walls and pistons and causing them to wear out of round. This is considered to be one of the most important features of the invention and due stress must be laid thereon. Furthermore, lubricant within the crank case cannot become cut or diluted by gasoline in the cylinder inasmuch as the packing gland or stuffing box will 75 80 85 positively preclude the passage of any gasoline into the crank case.

While I have shown and described the preferred embodiment of the invention, it should be understood that I reserve the right 90 to make such changes in the form, construction and arrangement of parts as will not depart from the spirit of the invention or the scope of the subjoined claims.

Having thus described the invention, I 95 claim:

1. In an internal combustion engine, a crank case, a crank shaft journaled therethrough and having a crank portion, a cam shaft journaled through the crank case and 100 operatively connected with the crank shaft for being driven thereby, a cylinder block mounted upon the crank case and having a cylinder therein, a cylinder head at the upper end of the block, a cross head guide extending down into the crank case, a piston 105 slideable axially of the cylinder and cross head guide and carrying a cross head slidably mounted along the guide, a connecting rod connected with the cross head and with the 110 crank portion of the crank shaft, a pair of spaced pistons carried by the piston rod and one constituting a power piston and the other a charge compressing piston, valve means for permitting an explosive mixture 115 to be introduced within the cylinder beneath the compression piston, transfer means for conducting said compressed charge into the cylinder head, valve means for permitting the compressed charge to enter the upper end 120 of the cylinder and the side of the cylinder being provided with an exhaust port controlled by movement of the power piston.

2. In an engine of the character described, a cylinder, a piston rod located and movable axially of the cylinder and carrying spaced pistons, one piston constituting a power piston and the other a compression piston, valved means for permitting an explosive charge to enter beneath the compres- 125 130

sion piston, valved means permitting passage of the compressed charge from the space beneath the compression piston into the top of the cylinder, valve controlled means for controlling entrance of the compressed charge from the top of the cylinder into the cylinder, and the side of the cylinder being provided with an exhaust port controlled by the power piston.

3. In an internal combustion engine, a crank case, a crank shaft journaled therethrough and having a crank portion, a cam shaft journaled through the crank case and operatively connected with the crank shaft for being driven thereby, a cylinder block mounted upon the crank case and having a cylinder therein, a cylinder head at the upper end of the block, a cross head guide extending down into the crank case, a piston slidable axially of the cylinder and cross head guide and carrying a cross head slid-

ably mounted along the guide, a connecting rod connected with the cross head and with the crank portion of the crank shaft, a pair of spaced pistons carried by the piston rod and one constituting a power piston and the other a charge compressing piston, valve means for permitting an explosive mixture to be introduced within the cylinder beneath the compression piston, transfer means for conducting said compressed charge into the cylinder head, valve means for permitting the compressed charge to enter the upper end of the cylinder and the side of the cylinder being provided with an exhaust port controlled by movement of the power piston, the operating means for the valves including cams on the cam shaft and push rods operatively connected with the stems of the valves and engaged by cams on the cam shaft.

In testimony whereof I affix my signature,
OSCAR J. ECKLAND.
